DESIGN FOR A COMBINED CABINET AND DOUCHE TANK

Chesley L. Wolfe, Richmond, Calif.

Application September 20, 1946, Serial No. 133,462

Term of patent 14 years

(Cl. D33—19)

To all whom it may concern:

Be it known that I, Chesley L. Wolfe, a citizen of the United States of America, and a resident of the city of Richmond, in the county of Contra Costa and State of California, have invented a new, original, and ornamental Design for a Combined Cabinet and Douche Tank, of which the following is a specification, reference being had to the accompanying drawings, forming part thereof.

In the drawings:

Fig. 1 is a front perspective view showing my new combined cabinet and douche tank design, and

Fig. 2 is also a front perspective view, but showing the cabinet open.

The broken line disclosure of the connecting hose is for illustrative purposes only.

I claim:

The ornamental design for a combined cabinet and douche tank, substantially as shown and described.

CHESLEY L. WOLFE.
